UNITED STATES PATENT OFFICE.

LEWIS G. HOFFMAN, OF WATERFORD, NEW YORK.

DOOR-BOLT.

Specification of Letters Patent No. 25,335, dated September 6, 1859.

To all whom it may concern:

Be it known that I, LEWIS G. HOFFMAN, of the village of Waterford, in the county of Saratoga and State of New York, have 5 invented a new and useful Improvement on the Ordinary Door-Bolts now in Use, to be Made of Brass, Iron, or other Metal; and I do declare that the following is a full, clear, and exact description of the construction and operation of the same, reference being had to the annexed drawings, making 10 a part of this specification, in which—

Figure 1, is a perspective view, and Fig. 2 is a working view of the improvement. 15 My improvement consists in applying a barrel to the center of the flat side of the common bolt (see letter A) and in the barrel placing a wheel, on which wheel is placed a key pin, a steady pin and a small 20 lever or arm (see B). I then form the bolt with a slot in its center, (see C) capable of receiving the lever, which by applying the key, runs the bolt out or in, as may be desired. In order to prevent the bolt from 25 turning, thereby throwing the lever out of gear, I cut a suitable slot on the top of the

case which contains the bolt, (see D) in which is placed a pin to control its movement. On the end of the bolt I place a thumb piece, fitted to a collar, (see E) 30 which enables me, by the use of the fastening pin (see F) to open or close the bolt at pleasure. In order to make the bolt answer for a right or left handed door, I reverse the position of the bolt, and merely change 35 the fastening pin (F) from upper to lower, as may be demanded.

What I claim as my invention and desire to secure by Letters Patent is,

The combination of a common door bolt 40 with a barrel containing a wheel with an arm acting on a slot in the bolt, so that when operated by a key, the door may be fastened or unfastened on the outside, the whole being so constructed and arranged 45 as not to interfere with the ordinary mode of using the bolt on the inside.

LEWIS G. HOFFMAN.
